US00D953329S

(12) **United States Design Patent** (10) Patent No.: **US D953,329 S**
(45) Date of Patent: **** May 31, 2022**

(54) **DISPLAY**

(71) Applicant: **Dell Products L.P.**, Round Rock, TX (US)

(72) Inventors: **Yu Weng Alvin Sitoh**, Singapore (SG); **Erene Teo**, Singapore (SG); **Tiak Hooy Sim**, Singapore (SG); **Chun Long Goh**, Singapore (SG)

(73) Assignee: **Dell Products L.P.**, Round Rock, TX (US)

(**) Term: **15 Years**

(21) Appl. No.: **29/695,731**

(22) Filed: **Jun. 21, 2019**

(51) LOC (13) Cl. **14-02**

(52) U.S. Cl.

USPC **D14/375**

(57) **CLAIM**

We claim the ornamental design for a display, as shown and described.

DESCRIPTION

FIG. 1 is a front perspective view of the display comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

Broken lines shown in the drawings illustrate portions of the display, and form no part of the claimed design.

1 Claim, 6 Drawing Sheets
